ENGINE FAIRING OR CASING FOR AIRCRAFT.

1,321,070.

Specification of Letters Patent.

Patented Nov. 4, 1919.

Application filed March 25, 1919. Serial No. 284,971.

To all whom it may concern:

Be it known that I, JOHN DUDLEY NORTH, a subject of the King of Great Britain, residing at Burgh Apton, Norfolk, England, have invented certain new and useful Improvements in Engine Fairings or Casings for Aircraft, of which the following is a specification.

The object of the present invention is to provide an engine fairing or casing, hereinafter termed a casing, for use on aircraft, and particularly on aeroplane flying machines, in which the head resistance is reduced to a minimum while the cooling of the engine is effected in a most efficient manner, and at the same time to provide a construction which can be easily and economically manufactured.

The casing according to this invention consists primarily of two main elements, namely a structure, generally composed of sheet metal, which surrounds and partially incloses the engine, hereinafter termed the engine housing, and a further structure, hereinafter termed the nose spinner, which serves to close the forward end of the engine housing and which nose spinner is circular in transverse section, is fixed to the engine shaft and rotates therewith. The general external contour of the engine housing with the nose spinner combined, is of streamline section with the heads of the engine cylinders protruding radially through the casing into external longitudinal channels formed on the housing by sheet metal projecting structures, hereinafter termed ramps, fixed on the housing between the cylinders, the external surfaces of which ramps conform to the general streamline configuration of the entire structure; thus each cylinder head along with its valve gear projecting above the same, is located in such a channel between two adjacent ramps, bringing the cooling of the engine to a most efficient point, in that the valve gear is subjected to the full blast from the propeller, and the upper portion of the cylinder is subjected to a lesser blast of air but which is directed to pass between the cooling fins, and moreover the head resistance is reduced since the valve gear is the only engine part extending beyond the casing of general streamline contour.

The casing may be completed by adding an intermediate section of the casing to the

rear edge of the engine housing and a tail section to the rearward end of the intermediate section, these two casings being circular in transverse section and their external shapes being such that when combined they complete the streamline contour of the casing considered as a whole.

In the alternative, when the engine is mounted in the fuselage of a flying machine the intermediate and tail sections of the casing may be dispensed with since the fuselage may be constructed to take the place of these sections.

The invention will be described with reference to the accompanying drawings, whereon Figure 1 is a sectional elevation showing an example of construction of the casing in which the general streamline configuration is completed by certain sections located rearward of the engine housing, and Fig. 2 is a rear elevation of the engine housing having certain parts removed.

Fig. 3 is a side elevation illustrating the nose spinner and the engine housing, and Fig. 4 is a transverse section drawn to a larger scale than the previous figures and taken about the line X—Y of Fig. 3.

Referring to the drawings, the engine housing is composed of a sheet metal cylinder 1 formed with a number of slots 2, Figs. 3 and 4, opening out on the rear edge of the cylinder 1 and extending for a suitable distance in the direction of the axis of the cylinder.

Onto the parts of the cylinder 1 between the slots, sheet metal structures 3 are fixed, hereinafter termed ramps, each ramp having an outer external surface curved in the direction of the axis of the cylinder 1 and having substantially vertical sides, the ramps preferably extending somewhat beyond the rear end of the cylinder 1 and being cut away at an angle.

The engine, which is sufficiently indicated by dotted lines 4 in the drawings, is secured and supported in any suitable manner to the main structure of the machine, and in the example shown the engine is bolted up to the face of a plate 5 of pentagonal outline as shown at Fig. 2, which flanged plate 5 is secured to strut members 6 extending from the spars 7 and 8 of the machine, and to the angles of the flanged plate 5 is fixed a tube 9 bent into annular

shape, over which tube the rear end of the cylinder 1 is sprung and by which tube 9 the said cylinder 1 is supported.

With such a construction the upper ends 5 of the cylinders 10 of the engine project through the slots 2, and consequently the upper ends of the cylinders and any valve gear carried thereon, are located in the channel-ways formed between the ramps 3 10 of the housing, and thus, although the general outline of the external surface of the housing conforms to a streamline shape, yet the heads of the cylinders and the valve gear carried thereby are exposed to a blast 15 of air due to the action of the air propeller.

In order to close the otherwise open front end of the cylinder 1 of the housing, a sheet metal nose is fitted or fixed to the propeller shaft, this structure 11, hereinbefore termed 20 the nose spinner, being of such configuration that it forms the leading end of a streamline form, the next rearward portion of which is provided by the external outer surfaces of the ramps 3 of the engine housing. The nose spinner 11 may be fixed by 25 a bolt 12 proceeding from the end of the propeller shaft, and the rear part of the nose spinner 11 can be supported by wire spokes or the like 13 extending between a plate 30 14 fixed to the flange of the propelled hub 15, said spokes 13 extending to a ring or the like 16 fixed in the interior of the nose spinner 11.

Taking over the rear edge of the cylinder 35 1 of the engine housing, is a conical sheet metal ring 17, the rear portion or end 18 of the ring 17 corresponding in diameter to the outer surfaces of the ramps 3, and the forward edge of the ring 17 can be detachably secured onto the bent rearward edge 40 of the cylinder 1 of the housing by for instance the tensioned cable 19 encircling the structure, so that should it be required to detach the cylinder housing after the removal of the nose spinner 11 it can be drawn 45 forwardly from off the engine after releasing in the tensioned cable 19.

In the construction shown the intermediate annular section of the casing 20 takes 50 over the rear edge of the sheet metal ring 17, and also embraces externally the forward edge of a tail section 21 of the casing, which tail section 21 may be supported in any suitable manner by being connected to the structure of the machine. The intermediate section 20 and the tail section 21 together complete the streamline contour of the whole casing.

When it is desired to obtain access to the 60 carburetors or other engine details located at the rear of the engine the intermediate section 20 can be telescoped over the rear or tail section 21.

In the manufacture of the invention de- 65 scribed the nose spinner 11 and the tail sec-

tion 21 can be readily formed by the process of spinning; the ramps 3 can be formed by pressing and then fixed by riveting onto the cylinder 1 of the housing, and the said cylinder 1 of the housing can be rolled up and 70 seamed. The intermediate section 20, which is the removable portion, may be formed from sheet metal without beating.

What I claim as my invention and desire to secure by Letters Patent is:—

1. In engine casings for use on aircraft; an engine housing structure composed of sheet material to surround and partially inclose the aircraft engine, said housing being circular in transverse section and externally 75 of streamline curvature in longitudinal elevation, said housing having longitudinal channels corresponding in number to the radial cylinders of the engine, the base of each channel having an aperture to permit 80 the head of an engine cylinder to project therethrough to be acted upon by the air passing through said channel, said housing being open at its forward end, means for supporting said engine housing and for supporting the engine therein from the framework of the aircraft, and means for closing 85 the front open end of said engine housing and completing the frontal portion of the streamline engine casing. 90

2. In engine casings for use on aircraft; the combination with an engine housing structure composed of sheet material to surround and partially inclose the aircraft engine, said housing being circular in transverse section and externally of streamline curvature in longitudinal elevation, said housing having longitudinal channels corresponding in number to the radial cylinders 10 of the engine, the base of each channel having an aperture to permit the head of an engine cylinder to project therethrough to be acted upon by the air passing through said channel, said housing being open at its forward end, and means for supporting said 10 engine housing and for supporting the engine therein from the framework of the aircraft; of a front structure to close the front open end of said engine housing, and means for supporting said front structure from the 11 engine, said front structure being circular in cross section and of streamline contour in longitudinal elevation to form the frontal continuation of the general streamline contour of said engine housing. 12

3. In engine casings for use on aircraft, the combination of an engine housing structure composed of sheet material, to surround and partly inclose the aircraft engine, said engine housing comprising a housing cylinder to inclose the engine, means for supporting said engine within said housing cylinder and for supporting said housing cylinder from the framework of the aircraft, said housing cylinder having apertures through 13

- its circular wall one for each engine cylinder, through which apertures the heads of said engine cylinders project to the exterior, ramps fixed on the exterior of said sheet material housing cylinder, each ramp consisting of a box-like casing having substantially vertical sides and an outer face curved in longitudinal elevation to a streamline curvature, said engine cylinder heads being located in the longitudinal channels formed between said ramps, a front structure to close the front open end of said engine housing, said front structure being formed of sheet material circular in cross section and of streamline contour in longitudinal elevation to form the frontal continuation of the general streamline contour of said engine housing, and means for supporting said front structure from the engine.
4. In engine casings for use on aircraft; the combination of an engine housing structure composed of sheet material, to surround and partly inclose the aircraft engine, said engine housing comprising a housing cylinder to inclose the engine, means for supporting said engine within said housing cylinder and for supporting said housing cylinder from the framework of the aircraft, said housing cylinder having apertures through its circular wall one for each engine cylinder, through which apertures the heads of the said engine cylinders project to the exterior, said apertures extending to the rear edge of said housing cylinder to enable said engine housing to be placed over and removed from the engine by moving said housing in the direction of its axis, ramps fixed on the exterior of said sheet material housing cylinder, each ramp consisting of a box-like casing having substantially vertical sides and an outer face curved in longitudinal elevation to a streamline curvature, said engine cylinder heads being located in the longitudinal channels formed between said ramps, a front structure to close the front open end of said engine housing, said front structure being formed of sheet material circular in cross section and of streamline contour in longitudinal elevation to form the frontal continuation of the general streamline contour of said engine housing, and means for supporting said front structure from the engine.
5. In engine casings for use on aircraft; the combination of an engine housing structure composed of sheet material, to surround and partly inclose the aircraft engine, said engine housing comprising a housing cylinder to inclose the engine, means for supporting said engine within said housing cylinder and for supporting said housing cylinder from the framework of the aircraft, said housing cylinder having apertures through its circular wall one for each engine cylinder, through which apertures the heads of said engine cylinders project to the exterior, ramps fixed on the exterior of said sheet material housing cylinder, each ramp consisting of a box-like casing having substantially vertical sides and an outer face curved in longitudinal elevation to a streamline curvature, said engine cylinder heads being located in the longitudinal channels formed between said ramps, a front structure to close the front open end of said engine housing, said front structure being formed of sheet material circular in cross section and of streamline contour in longitudinal elevation to form the frontal continuation of the general streamline contour of said engine housing, and means for supporting said front structure from the engine.
6. In engine casings for use on aircraft; an engine housing structure composed of sheet material to surround and partially inclose the aircraft engine, said housing being circular in transverse section and externally of streamline curvature in longitudinal elevation, said housing having longitudinal channels corresponding in number to the radial cylinders of the engine, the base of each channel having an aperture to permit the head of an engine cylinder to project therethrough to be acted upon by the air passing through said channel, said housing being open at its forward end, a plate structure within said housing, means for fixing said engine to said plate structure, means for supporting said plate structure from the framework of the aircraft, a tube bent into annular shape and fixed on to said plate structure upon which tube said engine housing is supported, and means for securing said housing to said tube.
7. In engine casings for use on aircraft; the combination of an engine housing structure composed of sheet material, to surround and partly inclose the aircraft engine, said engine housing comprising a housing cylinder to inclose the engine, means for supporting said engine within said housing cylinder and for supporting said housing cylinder from the framework of the aircraft, said housing cylinder having apertures through its circular wall one for each engine cylinder, through which apertures the heads of said engine cylinders project to the exterior, ramps fixed on the exterior of said sheet material housing cylinder, each ramp consisting of a box-like casing having substantially vertical sides and an outer face curved in longitudinal elevation to a streamline curvature, said engine cylinder heads being located in the longitudinal channels formed between said ramps, a front structure to close the front open end of said engine housing, said front structure being formed of sheet material circular in cross section and of streamline contour in longitudinal elevation to form the frontal continuation of the general streamline contour of said engine housing, and means for supporting said front structure from the engine.

sheet material circular in cross section and of streamline contour in longitudinal elevation to form the frontal continuation of the general streamline contour of said engine housing, means for supporting said front structure from the engine, a conical sheet metal ring the forward smaller diameter edge of which conjoins the rearward edge of said housing cylinder while the rearward 5 larger diameter edge of said conical ring conjoins and is of a diameter corresponding to the outer rear edges of said ramps on said housing cylinder, a rear section of the casing located at a distance from the rear edge of 10 the conical ring aforesaid, and an intermediate conical section, the forward edge of 15 said intermediate section overlapping the rear edge of said conical ring while the rear edge of said intermediate section overlaps the rear or tail section of the casing, said 20 intermediate and rear sections completing the streamline form of the casing as a whole, said intermediate section being capable of being slid rearwardly over the tail section to expose the carbureters and other engine 25 parts.

In witness whereof I have hereunto set my hand in the presence of two witnesses.
